(74) Attorney, Agent, or Firm—Thomas L. Derry; Diana L. Charlton

(57) **CLAIM**

The ornamental design for a joy-stick, as shown and described.

DESCRIPTION

FIG. 1 is a front-left perspective view of a first embodiment of a joy-stick of our new design;

FIG. 2 is a left side perspective view thereof;

FIG. 3 is a rear perspective view thereof;

FIG. 4 is a right side perspective view thereof; and,

FIG. 5 is a top view thereof.

The bottom of the joy-stick is unornamented and is not seen in normal use.
